WASTE DISPOSAL DEVICE HAVING A DISCHARGE POCKET COVERED BY A SHREDDING SCREEN

Sidney L. Lockley, New Castle, Pa., and Archer W. Richards, Chagrin Falls, Ohio, assignors to Lockley Machine Company, New Castle, Pa., a corporation of Pennsylvania

Application January 7, 1953, Serial No. 329,954

4 Claims. (Cl. 241—46)

This invention relates to grinding or comminuting devices, and more particularly to devices of this kind which are commonly referred to as garbage grinders and which are useful in disposing of waste material.

An object of the present invention is to provide a novel form of comminuting device in which a screen extends across an outlet opening in a wall of the grinding chamber and in which the material to be comminuted is forced against and through the screen in response to a whirling motion imparted to such material.

Another object is to provide a novel comminuting device of this character in which the screen is also a shredding member having shredding elements thereon adjacent the openings thereof and presented toward the grinding chamber.

Still another object is to provide a novel comminuting device having a vertical-axis grinding chamber and a disk rotor operable in the chamber adjacent the lower end thereof in a relatively closely spaced running relation to the side wall and to a screen extending across an outlet opening in such side wall, and in which the rotor and screen have cooperating shredding elements thereon.

A further object is to provide a novel comminuting device of the character just mentioned in which portions of the outlet opening extend above and below the rotor, and in which the grinding chamber communicates with the outlet opening through an upper perforated portion of the screen and the space below the rotor communicates with the outlet opening through a lower serated portion of the screen.

Yet another object is to provide a novel comminuting device of the kind above indicated in which the shredding screen is a curved plate and the shredding elements are inwardly projecting shoulders or shearing edges formed by inwardly offset portions of the plate.

As a further object, this invention provides a novel comminuting device of the character above referred to in which the screen is held against seat means of the housing by a housing part which is removable to afford access to the screen from the exterior of the device.

It is also an object to provide a novel comminuting device of the character mentioned above in which the rotor is mounted on the shaft of a direct-connected electric motor and in which the motor is capable of limited shifting transversely of its rotation axis for varying the operating clearance between the rotor and screen.

The invention can be further briefly summarized as consisting in certain novel combinations and arrangements of parts hereinafter described and particularly set out in the claims hereof.

In the accompanying sheets of drawings, forming a part hereof:

Fig. 1 is a side elevation of a comminuting device embodying the present invention, the device being shown with certain portions thereof broken away;

Fig. 2 is a partial transverse section on a somewhat larger scale and taken as indicated by section line 2—2 of Fig. 1, but with an impeller of the rotor shown adjacent the shredding screen;

2

Fig. 3 is a partial vertical section taken substantially as indicated by section line 3—3 of Fig. 2 and further illustrating the cooperation of the impeller means with the shredding screen;

5 Fig. 4 is an elevation representing a face view of the shredding screen, with the screen in detached relation and as seen from the shredding side thereof;

Fig. 5 is a vertical section taken through the shredding screen on section line 5—5 of Fig. 4;

10 Fig. 6 is a fragmentary transverse section of the shredding screen on an enlarged scale and taken approximately as indicated by section line 6—6 of Fig. 4;

Fig. 7 is a side elevation of the rotor showing the same in detached relation; and

15 Fig. 8 is a plan view of the rotor.

The novel comminuting device 10 represents one practical embodiment of the present invention, and comprises in general, a grinding unit 11 and an electric driving motor 12, preferably a reversible motor, direct-connected with the grinding unit and located at the lower end of the grinder housing 13. The comminuting device 10 is here shown as being suspended from the bottom wall 14 of a kitchen sink, or the like, and with which the device is connected by a coupling 15 having a threaded connection 16 with the grinder housing 13. The coupling 15 holds the upper end of the grinder housing in clamped engagement with the sink wall 14 with a suitable packing 17 interposed therebetween and the axial passage of the coupling provides an inlet opening 18 through which the garbage or other material to be comminuted is introduced into the grinding chamber 20 of the grinding unit.

In addition to the housing 13, the grinding unit 11 comprises a rotor 21 operable in the grinding chamber 20 and connected with the shaft 22 of the electric motor 12. The grinding unit 11 also includes a retaining and shredding screen 23 located in the housing 13 and with which the rotor 21 cooperates, as will be further explained hereinafter.

40 The housing 13 is an upright hollow housing such that the grinding chamber 20 defined thereby, is a substantially vertical-axis grinding chamber. At its lower end, the housing 13 is provided with a transverse wall 24 forming the bottom wall of the grinding chamber and a depending annular flange or skirt 25 extending below such transverse wall. The depending flange 25 defines an upwardly extending pocket 25a in the underside of the housing 13. On one side of the vertical axis 26 of the grinding chamber 20, the housing 13 is provided with an outlet opening 27 in the side wall thereof and which connects the grinding chamber with the delivery passage 28 of a discharge nozzle or spout 29.

The outlet opening 27 is in the form of a pocket or recess opening radially through the side wall of the housing 13 and extending arcuately of the side wall of the housing for a substantial portion of the circumference of the grinding chamber. The arcuate extent of the screen 23 is shown in the drawings (Fig. 2) as being on the order of a 45 degree portion of the wall circumference of the grinding chamber 20, that is to say, a minor portion of such circumference and does not, in any case, exceed 90 degrees in arcuate extent. The outlet opening or pocket 27 is located with its lower edge substantially flush with the top surface 24a of the transverse bottom wall 24,

65 and extends vertically of the grinding chamber 20 for a distance such that a minor portion of the outlet opening is below the rotor 21 and a major portion of the outlet opening is above the rotor. The outer annular portion of the wall surface 24a preferably slopes downwardly and outwardly toward the side wall of the grinding chamber 20, as shown in Fig. 1.

70 The rotor 21 is a disk-shaped member having a depend-

ing hollow central hub or shaft portion 30 extending downwardly through a substantially central opening 31 of the transverse bottom wall 24 and telescopingly engaging the motor shaft 22. The rotor 21 is connected with the motor shaft by key and setscrew elements 32 and 33 provided in the hub portion 30 and is normally driven in a counterclockwise direction as indicated by the arrow 21^a. The motor shaft 22 and the rotor 21 are disposed with their rotation axes substantially coincident with the axis 26 of the grinding chamber.

Leakage of liquid out of the grinding chamber 20 and around the drive shaft means for the rotor 21 is prevented by a suitable packing 34 disposed around the hub portion 30, as shown in Fig. 1. The packing 34 has its upper end extending into an annular counterbore 35 of the rotor 21 and its lower end seated in a counterbore 36 of the transverse bottom wall 24.

The rotor 21 is located at the lower end of the grinding chamber 20 and relatively close to the bottom wall 24, but with an intervening space 37 therebetween. The annular rim portion 38 of the rotor is in relatively closely spaced running relation to the side wall of the housing 13 and to the shredding screen 23. The clearance space between the rim portion 38 and the side wall of the housing 13 is of such small width that only a small amount of liquid or waste material will pass downwardly from the grinding chamber 20 through this clearance space into the intervening space 37 beneath the rotor.

As shown in the drawings, the rotor 21 is provided with impeller lugs 39, in this instance two such lugs, located at substantially diametrically opposed points of the rotor and extending upwardly into the grinding chamber 20 from the top surface of the rotor. These lugs are located adjacent the rim portion 38 of the rotor and serve as an impelling means which imparts a rotary or whirling motion to the waste material contained in the grinding chamber and also act as shredding elements, as will be further explained hereinafter.

The screen 23 forms a portion of the side wall of the grinding chamber 20 and is preferably curved to substantially the same curvature such that the portion of the screen presented toward the grinding chamber will conform with, and constitute a substantially flush continuation of, such side wall of the grinding chamber. The screen can embody any one of various specific forms of construction and is here shown as comprising a generally rectangular metal plate having flat narrow vertical side flanges 40 and 41, and a body portion between the flanges and corresponding generally as to its lateral and vertical dimensions with the lateral and vertical dimensions of the outlet opening 27.

The screen 23 is mounted in the outlet opening 27 of the housing 13 by providing the housing with a pair of outwardly facing substantially parallel spaced vertical seats 42 and 43 located on opposite sides of the outlet opening and which are engaged by the vertical side flanges 40 and 41. The flanges 40 and 41 of the screen are clamped against the seats 42 and 43 by a pair of lug projections 44 and 45 of a housing section 46 which forms a cover for the outlet opening 27 outwardly of the screen. The housing section 46 also carries the above-mentioned discharge nozzle 29 having the delivery passage 28 therein.

The housing section 46 is connected with the main housing 13 by suitable screws 47, such that this housing section will be removable for affording access to the screen 23 and will permit removal or replacement of the screen from the exterior of the device. A suitable gasket 48 is interposed between the main housing 13 and the removable housing section 46.

The screen 23 is provided with numerous openings or perforations 50 which extend through the metal plate and are distributed over the curved body portion of the screen, that is, over the plate area which is exposed to the grinding chamber 20. The openings 50 can be formed in the

screen 23 by any suitable punching or drilling operations and are here shown as being disposed with their axes substantially parallel to each other. These openings are of a size suitable to the grinding operation intended to be performed by the comminuting device 10 and such that they will prevent the escape of pieces of the waste material from the grinding chamber until the waste material has been reduced to particles of a desired fineness and which particles will then be capable of passing freely through the screen openings. The openings 50 may, for example, be on the order of three sixteenths of an inch in diameter although holes of a larger or smaller size can be used if desired.

In addition to serving as a temporary confining means for the waste material, the screen 23 also comprises a shredding member with which the rotor 21 cooperates and which produces an effective shredding or comminuting action on the waste material contained in the grinding chamber 20. For this purpose, the screen 23 is provided with numerous shredding elements 51 distributed over the exposed or effective surface thereof and located adjacent to the openings 50 or the major portion of these openings. The shredding elements 51 are here shown as comprising arcuate shearing edges or shoulders 52 located on one side of the openings 50 and extending partway around such openings and exposed by the openings to the contents of the grinding chamber 20.

The shredding elements 51 are preferably formed by inwardly offset integral portions of the metal plate of the screen 23. These shredding elements can be formed on the screen 23 by any suitable operation carried out on the metal plate, such as a stamping or embossing operation. As here shown, the shredding elements 51 are in the form of forwardly protruding bosses which have been formed on the inner or front face 53 of the screen by the formation of recesses 54 in the rear or outer face of the plate. By the formation of these recesses in the outer face by means of suitable dies, some of the metal of the plate is displaced or offset inwardly causing the solid shredding elements 51 to be swaged or embossed on the inner surface of the metal plate while leaving the openings 50 as full-width circular openings. By locating the recesses 54 such that they partially overlap the openings 50 of the screen, the shredding elements 51 will be formed in such location that they constitute a portion of the side wall of the openings and such that the arcuate or crescent-shaped shearing edges 52 will be exposed to the grinding chamber by the openings. The screen 23 can be hardened or otherwise rendered wear resistant after the shredding elements 51 have been formed thereon.

The body of the screen 23 containing the openings 50 and the shredding elements 51 constitutes the major portion of the screen and, when the screen is assembled in the grinding unit 11 in the position shown in Fig. 1, this major or perforated portion of the screen extends above the rotor 21. The lower or minor portion of the screen is located substantially opposite the rim portion 38 of the rotor and is provided with shredding elements 56 which are of a different form than the shredding elements 51. The lower portion of the screen containing the shredding elements 56 is a serrated portion comprising a row of teeth 57 and slots 58 between the pairs of adjacent teeth. The teeth and slots are inclined upwardly and laterally in the direction of normal rotation of the rotor 21, and the teeth are tapered in width such that they have a minimum width at the lower end thereof and increase progressively in width therealong from their lower ends to their upper ends.

In the assembled position of the screen 23 in the housing 13, the rounded lower ends 40^a and 41^a of the side flanges 40 and 41 of the screen engage laterally extending shoulders provided on the housing at the lower ends of the vertical seats 42 and 43. This engagement of the rounded flange portions 40^a and 41^a with the housing

13, positions the screen 23 vertically of the outlet opening 27 such that the lower ends of the shredding elements 56 will be separated from the lower edge 27^a of the outlet opening by the intervening space 59. In this assembled position of the screen 23, the shredding elements 56 are disposed in an arcuately extending series across the lower portion of the outlet opening 27 and lie opposite the rim portion 38 of the rotor 21 in a relatively closely spaced relation to the latter, as shown in Figs. 1 and 3.

As shown in the drawings, the impellers 39 of the rotor 21 each comprise an upright lug formed as an integral part of the disk portion of the rotor. The lug is of a somewhat triangular shape having oppositely bowed convexly curved side walls 60 and 61 and a generally flat rearwardly sloping top wall 62. The outer side wall 61 conforms substantially to the curvature of the peripheral surface of the rim portion 38 of the rotor. The intersection of the side walls 60 and 61 occurs at a vertical apex line defining a relatively sharp leading edge 63 located at and extending above the peripheral surface of the rim portion 38, as shown in Figs. 7 and 8.

By reason of the shape just described above for the impeller lugs 39, it will be seen that the side surfaces 60 will present sufficient area to the waste material contained in the grinding chamber 29 that when the lugs are moved around the grinding chamber by the rotation of the rotor, the lugs will impart the above-mentioned rapid rotary or whirling movement to the waste material or to a mixture of such waste material and water. During such arcuate travel of the lugs 39 around the grinding chamber adjacent the side wall thereof, the sharp vertical leading edges 63 of the lugs will act as shearing edges and will produce a comminuting effect on the waste material.

The movement of the sharp leading edges 63 across the screen 23 will be in shearing relation to the shearing edges 52 of the shredding elements 51 and will thereby produce a further comminution or grinding of the waste material. The reverse slope of the top wall 62 of the impeller lugs 39 and the convexly curved shape of the side walls 60, render the lugs also effective as deflecting members or plow elements for freeing the rotor from a jammed condition when a reverse rotary movement is imparted to the rotor. During such a reverse rotary movement of the rotor, the inclined top wall 62 and the curved side wall 60 will be effective in deflecting waste material away from the screen 23 and toward the central axis 26 of the grinding chamber to thereby unload the driving motor and assist the same in correcting the jammed condition.

As shown in Figs. 7 and 8, the rotor 21 is provided with substantially diametrically opposed edge recesses 64 which extend into the impeller lugs 39 and into the rim portion 38. These recesses serve as relief spaces in the rotor and render the lugs 39 and the rim portion of the rotor more effective in their comminuting cooperation with the screen 23. During this cooperation, the side edges of the recesses 64 act as comminuting elements or shearing edges as they travel across the shredding elements 51 and 56 of the screen.

The whirling motion imparted to the waste material by the rotor 21 is a very important function in the operation of the comminuting device 10, because it results in the repeated movement of the pieces of waste material across the screen 23 and also because it causes such pieces of waste material to be subjected to centrifugal force by which they are pressed against the screen during their movement thereacross. This movement of the pieces of waste material across the screen 23 while being pressed thereagainst by centrifugal force, causes the waste material to be subjected to a very effective shredding or comminuting action by the shredding elements 51.

When the pieces of waste material have been reduced to a sufficient fineness by the comminuting or shredding action produced thereon by the rotor 21 and the shred-

ding screen 23, the particles pass through the screen openings 59 and are discharged through the nozzle passage 28. The centrifugal force acting on the particles of waste material and the water with which they are mixed, causes the ground material to be discharged through the nozzle passage 28 as a velocity stream without need for any mechanical pump means to be embodied in the comminuting device 10. Whatever portion of the waste material finds its way downwardly past the rim portion 38 of the rotor into the intervening space 37, will be discharged from beneath the rotor through the relatively clear open space 59 and through the slots 58 of the screen.

The electric motor 12 includes a housing 65 and is connected with the grinding unit 11 by being suspended from the depending flange 25 of the housing 13. For this purpose, an annular sheet metal bracket 67 is interposed between the grinding unit and motor and has the flat annular web portion 67^a thereof connected with the upper end of the motor housing by suitable screws 68. The bracket 67 includes an upturned annular flange 69 extending around and connected with the depending flange 25 by suitable screws 70. The bracket 67 also includes a frusto-conical hollow central portion 71 which extends upwardly into the pocket 25^a and accommodates the upper bearing boss 72 of the motor housing.

In accordance with another feature of the present invention, provision is made for varying the width of the running space or clearance between the impeller lugs 39 of the rotor 21 and the shredding screen 23. For this purpose, the holes of the flat annular bracket portion 67^a of the bracket 67 are made sufficiently large to permit a limited shifting of the motor 12 in a direction transverse to the grinding chamber axis 26. Such shifting movement imparted to the motor in one transverse direction, will reduce the clearance space between impeller lugs 39 and the screen 23, and shifting of the motor in the opposite direction will increase this clearance space.

The transverse shifting of the motor 12 for adjusting this running clearance of the impeller lugs 39 can be produced by adjusting screw means, such as the adjusting screw 73, which is here shown as having a threaded engagement 74 in the depending flange 25 at a point of the latter which is on the opposite side of the axis 26 from the shredding screen 23. The screw 73 has the inner end thereof in engagement with one of the flat side faces of a nut-shaped extension 75 of the upper bearing boss 72 of the motor. While the connecting screws 68 are in a slightly loosened condition, the adjusting screw 73 is rotated in one direction or the other for positioning the motor in accordance with the running clearance desired between the impeller lugs 39 and the screen 23.

The connection of the motor 12 with the depending flange 25 of the grinder housing by means of the annular bracket 67, results in an intervening annular space 76 between this flange and the rounded portion 12^a of the motor housing. An annular grille 77 having numerous openings therein, extends around the comminuting device in surrounding relation to the annular space 76 and with the upper and lower edges of such grille overlying the flange 25 and the motor housing 66. The grille 77 improves the general appearance of the comminuting device and also permits the passage of a flow of ventilating air therethrough in connection with the cooling of the motor 12. The grille 77 is secured in place in any suitable manner, such as by means of one or more screws connecting the same with the flange 69 of the bracket 67.

The comminuting device 10 also includes a conduit member 78, preferably of sheet metal, connected with the housing 13 and the motor 12 and extending vertically of the device externally thereof. The conduit member 78 forms a support for a control switch 79 and also provides a passage 80 to accommodate electric wires extending to the motor.

The motor 12 is preferably a reversible motor so that

reverse rotation can be imparted to the rotor 21 when desired for the purpose of releasing a jammed condition of the rotor and during which reverse rotation the impeller lugs 39 accomplish their clearing function explained above. The switch 79 is a reversing switch having a forward position in which the switch lever 79^a is shown in full lines in Fig. 1, and has a reverse position in which the switch lever 79^a extends in a downwardly inclined position opposite to its full line position. The switch lever 79^a also has an intermediate position corresponding with an "off" position in which the motor 12 is deenergized.

From the foregoing description and the accompanying drawings, it will now be readily understood that this invention provides a novel comminuting device which will operate efficiently and satisfactorily for the disposal of waste material and which is of a simple construction and does not require the use of any mechanical pump means therein. It will also be seen that this novel comminuting device utilizes a shredding screen with which the rotor cooperates and which performs the dual function of confining the waste material until it has been ground sufficiently fine to pass through the opening of the screen and also performs a comminuting or grinding action on the waste material during passage of the waste material thereover while the waste material is being pressed against the screen by centrifugal force. Additionally, it will be seen that novel adjustment means providing for relative shifting of the driving motor permits adjustment of the operating clearance between the rotor and the shredding screen.

Although the novel comminuting device has been illustrated and described herein to a somewhat detailed extent, it will be understood, of course, that the invention is not to be regarded as being limited correspondingly in scope, but includes all changes and modifications coming within the terms of the claims hereof.

Having thus described our invention, we claim:

1. In a comminuting device, a housing having side and bottom walls defining an upright work chamber adapted to receive material to be comminuted, said side wall having a discharge pocket therein facing toward said chamber, a rotor located adjacent to but spaced above said bottom wall and being operable to impart a whirling motion to material contained in said chamber, said pocket extending from said bottom wall to a point located a substantial distance above said rotor, and a shredding screen in said housing and extending across said pocket, said screen having a lower serrated portion and an upper perforated portion, the space between said rotor and bottom wall being in communication with said pocket through the serrated portion of said screen and said chamber being in communication with said pocket through the perforated portion of said screen.

2. In a comminuting device, a housing having side and bottom walls defining an upright work chamber adapted to receive material to be comminuted, said side wall having a discharge pocket therein facing toward said chamber, a rotor operable to impart a whirling motion to material contained in said chamber and comprising a disk member located adjacent to but spaced above said bottom wall and having the peripheral edge thereof in relatively close running relation to said side wall, said pocket being located with a major portion of its height extending above said disk member and a minor portion of its height ex-

10 tending below said disk member, a shredding screen in said housing and extending across said pocket, said screen having a lower serrated portion and an upper perforated portion, and lug means rotatable with and projecting above said disk member in relatively close running relation to said screen, the space between said disk member and bottom wall being in communication with said pocket through the serrated portion of said screen and said chamber being in communication with said pocket through the perforated portion of said screen.

15 3. In a comminuting device, a housing defining a work chamber adapted to receive material to be comminuted, said housing having a discharge outlet leading from said work chamber, a drive shaft projecting into said chamber, a rotor carried by said shaft and operable in said chamber, a screen extending across said outlet and forming a portion of the wall of said chamber, shredding elements on said screen and presented toward said chamber, impeller means on said rotor and movable thereby around said chamber and across said screen in relatively closely spaced running relation to the latter, means mounting said shaft for rotation and for shifting transversely of its rotation axis for varying the spacing of the running relation of said impeller means with said screen, and adjusting means adapted to cause such transverse shifting of said shaft.

20 4. In a comminuting device, a housing having side and bottom walls defining a substantially vertical-axis grinding chamber, said side wall having an outlet opening therein on one side of the vertical axis, an electric motor at the lower end of said housing and having a rotatable shaft disposed substantially on said vertical axis, a screen in said housing extending across said outlet opening and forming a portion of said side wall, a rotor mounted on and carried by said shaft and operable in said chamber adjacent said bottom wall, cooperating shredding elements on said screen and rotor and the shredding elements of the rotor being movable around said chamber in relatively closely spaced running relation to the shredding elements of said screen, means connecting said electric motor with the lower end of said housing and adapted to permit limited shifting of said motor in a direction transverse to said vertical axis, and adjusting screw means located on the opposite side of said axis and effective to cause such shifting of said motor for varying the spacing 25 of the running relation between said rotor and screen.
